UNITED STATES PATENT OFFICE.

ADOLPH MAGNUS, OF NEW YORK, N. Y.

DESIGN FOR A LAMP-SHADE.

42,921.

Specification for Design.

Patented Aug. 20, 1912.

Application filed June 17, 1912. Serial No. 704,242. Term of patent 7 years.

To all whom it may concern:

Be it known that I, ADOLPH MAGNUS, a citizen of the United States, residing in the city of New York, borough of Bronx, in the county and State of New York, have invented a certain new, original, and ornamental Design for a Lamp-Shade, of which the following is a specification, reference being had to the accompanying drawing, forming part thereof.

The figure is a side view of a lamp shade, showing my new design.

I claim:

The ornamental design for a lamp shade, as shown.

ADOLPH MAGNUS.

Witnesses:

CHARLES R. SEARLE.
GEORGE J. MAGNUS.
